DISTILLATION OF HYDROCARBON OILS

Filed April 4, 1925

UNITED STATES PATENT OFFICE

ROBERT E. WILSON, OF CHICAGO, ILLINOIS, ASSIGNOR TO STANDARD OIL COMPANY,
OF CHICAGO, ILLINOIS, A CORPORATION OF INDIANA

DISTILLATION OF HYDROCARBON OILS

Application filed April 4, 1925. Serial No. 20,632.

The present invention relates to improvements in methods of vacuum distillation of hydrocarbon oils, and in apparatus for use in connection therewith. It will be fully understood from the following description, illustrated by the accompanying drawings, in which a longitudinal sectional view of apparatus suitable for carrying the invention into effect is shown.

10 In the application of Watts et al., Serial Number 20,414 filed April 3, 1925, there is shown and described a process of vacuum distillation of hydrocarbon oils in which the vaporization of the desired proportion of 15 the oil being distilled is effected by means of heat supplied by superheated steam. The present invention relates more particularly to improvements in the methods and apparatus described in that application.

20 Referring more particularly to the drawings, the numeral 5 indicates a conduit by which the oil to be distilled is supplied. As pointed out hereinafter, this oil is preferably supplied directly from a preceding distillation apparatus in which it has been heated; for example, the last still of a battery of continuous fire and steam reducing stills. Superheated steam is supplied from any suitable source through the pipe 6 to the chamber 30 6^a, from which it passes through the expanding nozzle 7 into the reduced pressure chamber 8, which leads, in turn, to the conduit 8^a.

From the conduit 5 the oil to be distilled 35 passes through feed pipe 9, which is supported and properly centered within the steam expanding nozzle by means of the rod 10 which enters (and closes) a projecting portion 9^a of feed pipe 9, and is itself supported by the baffle 11. It is readily apparent that any other suitable centering and supporting means for the feed pipe 9 may be employed. At a suitable point within 40 the expanding nozzle 7 the feed pipe 9 is provided with openings 12, through which oil 45 is supplied to and atomized by the at least partially expanded steam.

Within the chamber 8 there is provided, opposite the opening of the expanding nozzle 7, the baffle 11 which is supported by spider

13 within the frustro-conical deflector 14, which tapers in the direction of movement of the spray of steam and oil through the chamber 8. Opposite the smaller end of the deflector 14 is provided a similar baffle 15, likewise supported in a tapering or frustro-conical deflector 16 by means of spider 17. To prevent the formation of a dead space back of deflector 14, the smaller end of deflector 14 is connected with the larger end of deflector 16 by means of the throat 18. The smaller end of the deflector 16 opens into the conduit 8^a through throat 19. At the end of the nozzle 7 there is provided a small projecting ring member 20 provided at its base with openings 21. Oil draining back to the nozzle collects back of ring 20 and drips through openings 21, being picked up and reatomized by the steam.

In carrying out the invention, superheated steam, say at atmospheric pressure and at 1000° to 1200° F., is supplied to the expanding nozzle 7, in which it is expanded to the pressure prevailing within the chamber 8 and conduit 8^a; say 25 to 100 mm. Hg. In passing through nozzle 7, as the steam is expanded, its temperature drops, its drop being a function of the drop in pressure and change in velocity of the steam. The oil supplied, which may suitably be a residue oil resulting from the fire and steam distillation of crude oil, comes preferably directly from the reduction stills at a temperature of 650 to 720° F. (usually 680-690° F.) and is fed through pipe 5, feed pipe 9 and openings 12 into the expanding nozzle 7. The openings 12 are located within the nozzle at a point where the steam is at least partly expanded, and at which its temperature is not over 800° F., and preferably not over 700° F. The oil is finely atomized by the swiftly moving current of steam and is projected forward in a spray into chamber 8, in which its velocity of flow is greatly diminished.

On entering chamber 8 the spray of steam and oil strikes the baffle 11, which is preferably metallic, and this aids the distribution of heat to the oil droplets, which tend to cool due to self-evaporation. The oil is reatomized as it leaves the sides of the baffle

and the mass of vapor and oil particles then travels on through the deflector 14, which directs it against baffle 15, where a similar action takes place. The mass of vapor and oil particles then moves forward through deflector 16 and throat 19 into conduit 8^a, in which steady flow of the mass is resumed. As described in the application of Watts et al., hereinbefore referred to, the conduit 8^a is so proportioned that the flow therethrough takes place at a rate of 200 to 600 feet per second (preferably 400 to 500 ft.) and it is of sufficient length to permit the attainment of substantial thermal equilibrium therein, this being materially aided by the action of the baffling devices 11 and 15. In passing through the chamber 8 a substantial quantity of heat reverts to the mass of vapor and oil, resulting in an increase of temperature and materially aiding the desired vaporization of the oil. The mass of oil and vapor passes from conduit 8^a to suitable separating devices for the removal of unvaporized oil, condensers and evacuating devices, as fully set forth in the application of Watts et al., hereinbefore referred to. As these are not a part of the present invention, they are not further described and illustrated herein.

I claim:

- 30 1. In apparatus for the distillation of hydrocarbon oils, an expanding nozzle, means for supplying superheated steam to said nozzle, means for supplying oil at an intermediate point in said nozzle, an enlarged conduit into which said nozzle opens, a fixed metallic surface in said conduit opposite the opening of said nozzle against which the oil droplets are impinged, the area of the metallic surface presented to said nozzle being sufficient to receive the entire jet therefrom, and means for reatomizing the oil and directing the mass of vapor and oil particles forwardly through the conduit.
- 45 2. In apparatus for the distillation of hydrocarbon oils, an expanding nozzle, means for supplying superheated steam to said nozzle, means for supplying oil at an intermediate point in said nozzle, an enlarged conduit into which said nozzle opens, means for maintaining said conduit at reduced pressure, a metallic surface in said conduit opposite the opening of said nozzle, and a forwardly tapering deflector surrounding said surface and adapted to direct the mass of vapor and oil particles forwardly through the conduit.
- 55 3. In apparatus for the distillation of hydrocarbon oils, an expanding nozzle, means for supplying superheated steam to said nozzle, means for supplying oil at an intermediate point in said nozzle, an enlarged conduit into which said nozzle opens, means for maintaining said conduit at reduced pressure, a baffle in said conduit opposite the opening of said nozzle, a baffle spaced for-

wardly of said first baffle, and means for directing the mass of vapors and oil particles from around the first baffle forwardly against the second baffle.

4. In apparatus for the distillation of hydrocarbon oils, an expanding nozzle, means for supplying superheated steam to said nozzle, means for supplying oil at an intermediate point in said nozzle, an enlarged conduit into which said nozzle opens, means for maintaining said conduit at reduced pressure, a baffle in said conduit opposite the opening of said nozzle, a baffle spaced forwardly of said first baffle, and a forwardly tapering deflector surrounding the first baffle and terminating opposite the second baffle, thereby directing the mass of vapor and oil particles forwardly against the second baffle.

5. In apparatus for the vacuum distillation of hydrocarbon oils, an expanding nozzle, means for supplying superheated steam to said nozzle, means for supplying oil at an intermediate point in said nozzle, an enlarged conduit into which said nozzle opens, means for maintaining said conduit at reduced pressure, a baffle in said conduit opposite the opening of said nozzle, a baffle spaced forwardly of said first baffle, a forwardly tapering deflector surrounding the first baffle and terminating opposite the second baffle, thereby directing the mass of vapor and oil particles forwardly against the second baffle, and means for directing the mass of vapor and oil particles from around the latter baffle forwardly through the conduit.

6. In the distillation of hydrocarbon oils, expanding superheated steam through an expanding passage into an enlarged conduit at reduced pressure, supplying oil to the at least partially expanded steam before entering said conduit, impinging the oil particles against an obstructing surface on entering the conduit, reatomizing the oil and causing the mass of vapor and oil particles to come to steady flow through said conduit at a rate of 200 feet per second or higher.

7. In the vacuum distillation of hydrocarbon oils, expanding superheated steam through an expanding passage into an enlarged conduit at reduced pressure, supplying oil to the at least partially expanded steam before entering said conduit, impinging the mass of vapor and oil particles against a surface within said conduit and subsequently causing the mass of vapor and oil particles to move forwardly through the conduit in steady flow at a rate of at least 300 feet per second.

ROBERT E. WILSON.

DISCLAIMER

1,758,590.—*Robert E. Wilson*, Chicago, Ill. DISTILLATION OF HYDROCARBON OILS.
Patent dated May 13, 1930. Disclaimer filed August 29, 1930, by the assignee,
Standard Oil Company.

Hereby enters this disclaimer to claim 7 of said patent, which is in the following words, to wit:

“7. In the vacuum distillation of hydrocarbon oils, expanding superheated steam through an expanding passage into an enlarged conduit at reduced pressure, supplying oil to the at least partially expanded steam before entering said conduit, impacting the mass of vapor and oil particles against a surface within said conduit and subsequently causing the mass of vapor and oil particles to move forwardly through the conduit in steady flow at a rate of at least 300 feet per second.”
